UNITED STATES PATENT OFFICE.

ERNEST SCOTT, OF HUDSON, MASSACHUSETTS, ASSIGNOR OF ONE-HALF TO J. KEYES HALL,
OF MAYNARD, MASSACHUSETTS.

WRAPPING MECHANISM.

No. 914,316.

Specification of Letters Patent.

Patented March 2, 1909.

Application filed October 21, 1907. Serial No. 398,318.

To all whom it may concern:

Be it known that I, ERNEST SCOTT, a citizen of the United States, residing at Hudson, in the county of Middlesex, Commonwealth of Massachusetts, have invented an Improvement in Wrapping Mechanism, of which the following description, in connection with the accompanying drawings, is a specification, like numerals on the drawings representing like parts.

This invention relates to wrapping mechanism, and more especially relates to mechanism for wrapping magazines or books.

In order that the principles of the invention may be fully understood, I have disclosed a single type or embodiment thereof in the accompanying drawings, wherein—

Figure 1 is a vertical, longitudinal section taken upon the broken line 1—1 of Fig. 2; Fig. 2 is a plan view of the mechanism, but broken away at opposite sides. Fig. 3 is a transverse, vertical section upon the broken line 3—3 of Fig. 2; Fig. 4 is a side elevation of the mechanism shown in Fig. 2 from the left hand side thereof viewing said figure; Fig. 5 is a plan view of the carrier and parts directly associated therewith; Fig. 6 is a central, vertical, longitudinal section of a portion of the means for operating the tray; Fig. 7 is a detail, in vertical section, of the cam and connected parts for controlling the path of movement of the conveyer arm; and, Fig. 8 is a detail of the cam and associated parts for operating the tray.

Referring more particularly to the single type or embodiment of the invention herein represented, the framing of the machine, which may be of any material, construction and form, is indicated at 1 in each of the figures. Mounted between the uprights of said framing, as most clearly indicated in Figs. 1, 3 and 4, is a main shaft 2 having thereon (Fig. 3) a pulley 3, by which power may be applied from any suitable source. Likewise mounted in said framing (Figs. 1 and 3) is a countershaft 4, herein shown as parallel with the shaft 2 and having thereon a gear 5 meshing with and driven by the gear 6 upon the main drive shaft 2. It is apparent that the wrapper may be delivered to the mechanism by hand or otherwise. Preferably, mechanism is employed to deliver the wrappers in section from a continuous web, separating the web into proper lengths as the material is fed. While any

desired mechanism may be employed, for this purpose I herein mount upon the counter-shaft 4 (see Fig. 3) a beveled gear 7 meshing with a similar gear 8 upon a substantially vertical shaft 9 mounted in suitable hangers in the main frame and having near the upper end thereof a beveled gear 10 meshing with a similar gear 11 upon a stud 12, suitably mounted in the framing of the machine and having thereon a gear 13 meshing with gear 14 upon a shaft 15 mounted in the framing of the machine.

As more clearly represented in Fig. 1, in suitable hangers in the framing of the machine is mounted a roll of paper 16, and upon the shafts 12 and 15 respectively are mounted drums 17 and 18 positively driven by the gearing described and adapted in their rotation to draw the paper at a proper rate of speed from the roll 16. Any suitable means may be employed to separate the web of paper into proper lengths to serve as wrappers. Herein one of the drums as 17 is represented as provided with a longitudinal groove 19 upon the periphery thereof and the other drum with a co-acting knife 20, whereby during each rotation of said drums a length of web to serve as a wrapper is severed from the leading end of the web. At the delivery side of said rolls 17 and 18 is mounted a guide way 21, herein shown as downwardly inclined. Mounted below and above the upper face of said guideway are small drums 22, 23, 24 and 25 arranged in pairs and adapted to receive thereon belts 26 and 27, the adjacent faces whereof are disposed substantially in the plane of the upper face of the guide way 21 to receive therebetween the severed wrapper and to deliver the same in the direction of the arrow onto the working table.

The working table is indicated in Figs. 1 and 2 at 28. Such table may be of any suitable construction, but preferably is horizontally disposed to provide a flat receiving surface, upon which the wrapper is delivered from the guide way 21. The wrapper is delivered onto said table so that the forward or leading edge of the wrapper extends beyond the line of the corresponding edge of the magazine or book or other article to be wrapped. In the mechanism herein represented and viewing Fig. 1, the leading edge of the wrapper may extend to about the point 29. It is apparent that the article to

be wrapped may be positioned upon the wrapper in any suitable manner, either by hand or otherwise. Assuming the mechanism to be employed to wrap a magazine and that a magazine has been positioned upon the wrapper fed to the operating table so that the leading edge of the wrapper extends beyond the corresponding edge of the magazine, which edge, in this type of the invention, is one of the free edges thereof, I apply such leading edge of the wrapper to the free edge of the magazine. While this may be done in various ways, I herein separate the leaves of the magazine to a suitable extent and place between such separated leaves such leading wrapper edge, thereafter permitting the magazine to close. It is apparent that this result may be accomplished in many ways. Herein for the purpose I employ a working head 30 and mount the same for horizontal reciprocation (see Figs. 1 and 2) in suitable guide ways 31 formed upon the inner faces of the webs 32 and 33 of the framing, shown most clearly in Fig. 2. Also mounted for reciprocation upon the main framing is an auxiliary carrier 34 guided upon ways formed upon the outer faces of the webs 32 and 33 of the framing, said auxiliary carrier being mounted, as shown also in Fig. 1, above the working head but adapted to reciprocate in a path parallel therewith. Mounted upon the auxiliary carrier (see Figs. 1 and 2) is a rock arm 35 carrying thereon a forwardly extended magazine leaf opener 36, which, as shown in Fig. 2, is a relatively narrow, sharply pointed blade secured at its base to an arm 37 having upon its under face an angular portion 38 (see Fig. 1). Fast upon and upstanding from the rock shaft 35 is an arm 39. In the forward movement of the working head 30, the leading face 40 thereof engages at its upper edge the angular portion 38 of the opener, so that in the further forward movement of said working head the auxiliary carrier is forwardly moved and the point of the opener is inserted between the pages of the magazine.

Pivotedly mounted in suitable uprights, as indicated in Figs. 1 and 2, is a rock shaft 41 having mounted thereon a pair of wrapper end positioning members 42 and 43, extending first downwardly, and then forwardly in a horizontal direction from said rock shaft. In the normal position of said shaft 41, the members 42 and 43 lie in a horizontal plane beneath the plane of the wrapper when positioned upon the operating table with the outer or leading ends thereof beneath the leading or free edge of the wrapper, so that when said members are swung upwardly, by reason of the partial rotation of said rock shaft 41, the free edge of the wrapper is lifted. While any suitable means may be employed to rock the

shaft 41, herein for the purpose I provide upon the working head (see Figs. 1 and 2) a latch 44 pivoted at 45' and normally held by spring 46 in a position normal to the path of movement of the working head. Said latch, as represented most clearly in Fig. 1, is provided with an inclined head 44'. Said latch, as represented in Fig. 1, is adapted in the movement of the working head toward the magazine to move under 75 the rock shaft 41 and to contact with the downwardly extending portion 34', and upon a continuation of such movement of the working head to rock said shaft so as to lift the free edge of the wrapper, as stated. 80 During the continued movement of the working head 30 toward the magazine, the arm 39 of the rock shaft 35 engages an upstanding lug 47 (see Fig. 1) upon the frame of the machine, the shaft 35 being 85 thereby rocked, thus lifting the opener 36 and opening the magazine. The timing of the parts is such that the lifting of the opener 36 preferably slightly precedes or is simultaneous with the lifting of the free 90 edge of the wrapper by the members 42 and 43, the upstanding edge of the wrapper being as shown preferably of greater height than the thickness of the magazine. Projecting forwardly from the working head 95 30 (see Fig. 2) and upon opposite sides of the opener 36 are wrapper inserters 48 and 49. Such inserters terminate short of the forward edge of the opener and preferably occupy a plane substantially that occupied 100 by the opener when it is inserted into the magazine. Upon the continued movement of the working head toward the magazine, the opener having been swung upwardly and carrying with it a portion of the pages 105 of the magazine, the wrapper inserters 48 and 49 engage the upstanding edge of the wrapper, and in their continued onward movement insert the same between the open leaves of the magazine. The engagement of 110 the arm 39 of the rocker 35 with the lug 47 of the frame of the machine results in the upward swinging of the opener 36, as already stated, and also in the disengagement of said opener from the working head by 115 reason of the fact that the angular portion 38 of said opener is lifted above the upper edge of the face 40 of the working head. Thus, further onward movement of the 120 opener is prevented. The movement of the working head is, however, continued with the result that the forward face 40 thereof engages the edge of the magazine, pushing the same to the right viewing Fig. 1, thus separating the opener 36 and the magazine, 125 which is then permitted to close upon the inturned edge of the wrapper.

To the right, viewing Fig. 1, of the operating table 28 is a delivery throat 50, the upper wall whereof is formed by the for- 130

ward portion of the guide way 21. The described onward movement of the working head 30 pushes the magazine and the wrapper which underlies the magazine into said throat. In order that the wrapper may be drawn taut to the magazine, I provide any suitable mechanism to engage the rear end of the wrapper to draw upon the same or prevent too free movement of the wrapper. For the purpose, in this embodiment of the invention, I employ (see Fig. 1) a stretcher roll 51 mounted upon an arm of a bell crank lever 52, the oposite arm whereof is provided with a roll 53 to engage at the proper time a cam 54 formed upon a disk 55 mounted upon a shaft 56 suitably mounted in bearings in the frame of the machine. A spring 57 connected to the lower arm of the bell crank lever tends to draw the roll 53 mounted upon said arm toward the shaft 56, so that normally the stretcher roll 51 contacts with the upper face of the lower or forward portion of the guide way 21. The timing of the parts is such that before the forward edge of a wrapper that is being fed into position by the belts 26 and 27 reaches said roll, the latter is lifted from the guide way 21 by the engagement of the cam 54 with the roll 53, the stretcher roll 51 remaining elevated until the wrapper has been positioned to receive the magazine, after which the said roll is permitted to descend and engages the upper face of the wrapper with sufficient force to impart tension thereto and to render it taut as the magazine is pushed into the delivery throat 50, as above stated.

Fast upon the shaft 56 is mounted (Fig. 1) a magazine receiver 58. While such receiver may be of any suitable construction, so as to receive any desired number of magazines, preferably I provide the same with a plurality of pockets and impart a motion thereto preferably intermittent, so as to bring said pockets in succession into alignment with the delivery throat 50, so that upon the continued movement of the working head 30 a magazine may be inserted into a pocket of the receiver. In the preferred embodiment of the invention, I provide the receiver with two pockets 59 and 60, the inner side walls 61 and 62 whereof may be solid. The bottom 63 of each pocket is, however, formed of spaced webs extending from the solid side walls 61 and 62 respectively, the outer side walls 64 and 65 of said pockets being formed as continuations of such spaced webs and lying preferably in parallelism with the inner side walls 61 and 62. It is apparent that the outer side walls 64 and 65 of the pockets may be unbroken or may merely form continuations of the spaced webs 63. If desired, the webs 63 and walls 64 and 65 may be of some material that is sufficiently resilient to permit the

yielding of said outer walls during the insertion of the magazine, so that the magazines may be snugly received within the pockets. Preferably the leading edges of the walls of the pockets 59 and 60 are outwardly flared, as represented at 66.

In the present embodiment of my invention, I apply an adhesive to the wrapper, and preferably to the rear end thereof. While the adhesive may be applied to the wrapper in any suitable manner and at any desired time, I herein apply the same to such end of the wrapper after the passage of the magazine through the throat 50 when the magazine is wholly inserted in a pocket of the receiver. In order to accomplish such result, I provide (see Fig. 1) a paste tank 67 and mount therein a roll 68 driven by a belt 69 from the shaft 4. If desired, I may provide a doctor roll 70 contacting with the paste roll 68. Pivoted upon the frame of the machine, as indicated at 71' (see dotted lines Fig. 1), are levers 72 (see Fig. 3), the lower ends whereof are provided with rolls 73, one of which engages a cam way 90 74 in the cam 75 and the other of which engages a similar cam way in the gear 5. The upper free end 71 of said levers are connected (see Fig. 1) to links 76, provided upon the opposite ends whereof is a roll 77 95 mounted upon links 77' (see dotted lines Fig. 1) suitably secured in the frame of the machine. The roll 77 is adapted to engage with the paste roll 68 and intermittently to be lifted therefrom and to be brought into engagement with the under face of the rear end of the wrapper extending from that edge of the magazine that receives the leading edge of the wrapper. Such engagement of the paste roll with the wrapper takes place as such edge passes beneath the under face of the guide way 21 forming the throat 50, said under face of the guide way forming a backing or abutment for such portion of the wrapper as it is drawn past the paste roll 77 during the final portion of the forward movement of the working face 30.

Any suitable means may be employed intermittently to rotate the receiver 58. Herein for the purpose I provide (see Fig. 1) a gear 78 fast upon the shaft 56 and having at diametrically opposed points circumferentially enlarged teeth 79. Fast upon the shaft 4 is mounted a gear 80 having thereon a series of teeth 81 occupying but a portion 115 of the periphery of the gear. During the rotation of said gear 80, the teeth 81 thereof engage the teeth of the gear 78 and impart a movement of semi-rotation thereto, such movement terminating with the engagement 120 of one of the teeth 79 with a portion of the periphery of the gear 80 unprovided with teeth.

The timing of the parts is such that the gear 78 is held stationary when one of the 130

pockets of the receiver 58 is brought into alignment with the delivery throat 50, as is indicated in Fig. 1, the receiver remaining stationary until the magazine has been fully 5 inserted in the pocket 59 thereof. Thereupon the teeth of the gear 80 reengage the teeth of the gear 78 and impart a further movement of semi-rotation to the receiver, thereby bringing the filled pocket into the 10 position occupied by the lower pocket shown in Fig. 1, whereupon the teeth of the gears 80 and 78 become disengaged, and the receiver remains stationary until the magazine has been ejected from the lower pocket and 15 another magazine has been inserted in the pocket next brought into alignment with the operating table.

Any suitable means may be employed to 20 eject the magazine from a filled pocket. To simplify the construction of parts, I prefer to employ a common means for operating the working head and the ejector, which latter, in the present type of the invention, is indicated (see Fig. 1) at 82, being mounted 25 for horizontal reciprocation in suitable guide ways 83 formed in the framing of the machine. Mounted upon a stud 84 in the framing of the machine is a bell crank lever, the shorter, lower arm 85 whereof is provided with a roll 86 adapted to engage a 30 cam path 87 formed in a cam 88 fast upon the countershaft 2. The other arm 89 of the bell crank lever is suitably connected by a pin and slot connection 90 with an up- 35 standing portion or web 91 projecting from the upper face of the ejector 82. The rotation of the shaft 2 by reason of the engagement of the roll 86 with the cam path 87 imparts a horizontal reciprocation to the 40 ejector 82, whereby the latter is brought into engagement with the magazine when the filled pocket thereof is brought into the path of such ejector. The leading edge 92 of the 45 ejector is formed of spaced members or fingers adapted to enter between the spaced webs of the pockets of the receiver to eject the magazine therefrom.

In the present embodiment of the invention, the construction and location of the 50 ejector and the working head and the functions of said parts are such that preferably I impart a differential movement to said members. Herein, the movement of the 55 ejector. This result may be accomplished in any desired manner. For the purpose, I have provided, upon the framing of the machine and above the ejector, a stationarily 60 mounted horizontal rack or racks 93, and upon a web 94 uprising from the rear of the 65 ejector 82, I provide a bearing to receive a short shaft 95 having thereon a pinion or pinions 96 to engage said rack or racks, and upon the lower face of the working head 30 I provide a rack or racks 97 to mesh with 65 said pinion or pinions.

From the described construction, it will be apparent that, during either movement of reciprocation of the ejector 82, the pinion or pinions 96 are moved bodily with said ejector at the same speed and also they rotate upon 70 their axes by reason of their engagement with the stationary rack, thereby imparting movement to the working head at a speed double that of the ejector 82. The rear pasted edge of the wrapper may be folded 75 down upon the body thereof in any suitable manner at the time desired. Hereto for the purpose, I provide (Fig. 1) a pair of loose rolls 98 and 99. The lower roll 98 is mounted in stationary bearings to rotate in the 80 plane of the face of the magazine as it is ejected from the pocket 60. The upper roll 99 is mounted upon the lower end of a lever 100 pivoted upon the framing of the machine at 101 and having intermediate its end 85 a roll 102 adapted to engage a cam path 103 in the face of a cam 104 mounted upon the shaft 56. The form of the cam path 103 is such that, during the rotation of the receiver 58, the roll 99 is moved outwardly or 90 to the right, viewing Fig. 1, thereby to remove the same from the path of rotation of the receiver. At the termination of each movement of semi-rotation of the receiver, such roll is returned to its inner position, so 95 that the lower portion of the periphery thereof may engage the wrapped magazine as the same is ejected from the filled pocket 60. It will be apparent from the foregoing description that when a filled pocket is, by 100 the semi-rotation of the receiver 58, moved from the upper to the lower position, the protruding rear pasted end of the wrapper extends from the pocket as indicated at 105, in Fig. 1, so that when the roll 99 is permitted to move inwardly it is brought into engagement or juxtaposition to said end 105. As the magazine is ejected from the pocket, the said end 105 of the wrapper passes beneath the roll 99 and is thereby folded down 110 against the body of the wrapper and pasted thereto. The magazine, when ejected from a pocket of the receiver, falls upon an inclined way 106, and may be discharged into any suitable receptacle. 115

Thus far, reference has been made to the placing of a magazine upon a wrapper when the latter is positioned upon the operating table 28. It is apparent that the magazines or other articles that are to be wrapped may 120 be placed by hand upon such wrapper. I prefer, however, to employ mechanism operating automatically so to position the magazine or other article. While any suitable mechanism may be employed for the purpose, I have herein represented (see Figs. 1, 3 and 5) a pair of endless chains 107 constituting a carrier, said chains being mounted upon suitable drums or gears 108 and 109 fast upon shafts 110 and 111 suitably mounted 125 upon the operating table 28.

ed in the framing of the machine. Certain of the links of the chain 107 are provided with T-shaped members 112, the head 113 whereof having a facing plate 113' is preferably provided at opposite ends with rolls 114 adapted to engage an annular flange portion of the drums 108 and 109 to overlie and engage the adjacent links of the chain so that the foot 115 of each member may be supported and act as a shelf to receive thereon one or more articles to be delivered to the wrapping mechanism. Viewing Figs. 1 and 3, it will be apparent that as the endless chains travel in the direction of the arrow represented in Fig. 1 each shelf 115 may receive thereon at the proper time one or more articles, such as magazines, the operative preferably placing the magazines or other articles in place during such upward movement of the shelves.

Power may be applied to the carrier 107 in any suitable manner. Herein upon the shaft 110 is mounted a beveled gear 116 (see Figs. 1 and 3) wherewith meshes a similar gear 117 loose upon the upper end of a vertically disposed shaft 118 mounted in suitable hangers in the framing of the machine and provided at its lower end with a beveled gear 119 meshing with a similar gear 120 mounted upon the counter-shaft 4. Formed with the pinion 117 is one member 121 of a clutch, the opposed member 122 whereof is splined upon the shaft 118 and is provided with an annular groove 123. From the foregoing description, it will be apparent that upon engagement of the clutch members 121 and 122 the gear 116 is rotated thereby to drive the carrier. The magazines or other articles positioned upon the carrier may be discharged therefrom in any suitable manner. Preferably I discharge the magazines singly and while the carrier is stationary. To that end, I herein permit the leading magazine upon the carrier to control the movement of the carrier. As represented in Fig. 3, the upper magazine 124 of the stack of magazines is adapted to be ejected to the right, viewing said figure. The upper face of the leading magazine engages a roll 125 (see also Fig. 5) mounted upon an arm 126 of a lever pivoted at 127, a second arm 128 of said lever having a roll thereon received within the annular groove 123 of the clutch member 122. A third arm 129 of said lever has attached thereto one end of a coil spring 130, the opposite end whereof is attached to any suitable point on the framing of the machine, said spring tending normally to move said member 122 of the clutch into engagement with the member 121 to drive the carrier 107. During the upward movement of the magazines upon the carrier, the leading magazine encounters the roll 125 upon the lever arm 126 and in the continued onward

movement of the magazine the clutch member 122 is disengaged from the clutch member 121, and the carrier 107 is thereby stopped. As the leading magazine 124 is ejected in a manner to be described, the roll 125 is permitted to drop, whereupon the spring 130 reengages the members of the clutch, whereby the carrier is moved onward sufficiently to bring the next magazine or other article into engagement with the roll 125 and again disengage the clutch members 122 and 121. In the present embodiment of the invention, I have (see Figs. 2, 3, and 5) notched one face of each shelf 115 as indicated at 131 to permit the described movement of the arm 126 carrying the roll 125.

Any suitable means may be employed to convey the magazines or other articles singly from the carrier 107 to the operating table. Herein for the purpose, I preferably provide a conveyer to move the topmost magazine or other article into a suitable tray or the like, which, in turn, is moved in any suitable manner to deposit the magazine upon the wrapper when positioned upon the operating table. As represented most clearly in Figs. 2 and 4, I pivotally mount in bearings 132 in the framing of the machine a lever arm 133 having mounted thereon intermediate its ends a roll 134 adapted to engage a cam path 135 in a cam 136 mounted upon a shaft 137 (see Figs. 3 and 4) having thereon a beveled gear 138 meshing with and driven by a similar gear 139 (see also Fig. 2) mounted upon the main driving shaft 2. The upper end of the lever 133 (see Fig. 4) is connected by a pin and link connection 140 with a sliding head 141 mounted for horizontal reciprocation upon guide ways 142 in the framing of the machine.

As shown more clearly in Fig. 5, pivotally mounted near the rear end thereof in ears 143 rising from the sliding head 141 is a conveyer arm 144 which partakes of the longitudinal reciprocation of the sliding head and, owing to the described pivotal mounting thereof, may swing in a plane normal to that of the path of reciprocation. Extending rearwardly from the pivot of said conveyer arm 144 is a lug 145 adapted to engage (see Figs. 4 and 7) a cam path 146 formed in a portion 147 mounted upon the framing of the machine. Said cam path comprises upper and lower horizontal portions connected at the ends as indicated and having adjacent the inner end a pivotal latch 148. In the operation of the parts, movement toward the right is imparted to the sliding head 141 by means of the lever 133 and cam 136, the conveyer arm 144, at such time, occupying a horizontal position with the lug 145 within the upper portion of the cam path 146, so that in the inward movement of

the sliding head 141 or toward the right, viewing Fig. 4, said conveyer arm moves in the plane of the topmost magazine and pushes the same from the carrier 107, whereupon, in the manner already described, the carrier is intermittently moved to bring the next magazine into the plane formerly occupied by the one just pushed from the stack of magazines. Toward the limit of the inward movement of the conveyer arm 144, the lug 145 thereof depresses the spring pressed latch 148, and upon the continued inward movement of said conveyer, said latch returns to the position indicated in Fig. 4, whereupon in the outward movement of the sliding head 141 or to the left viewing Fig. 4 said lug is compelled to traverse the lower portion of the cam path 146 with the result that during the return movement the conveyer arm 144 assumes a vertical position so as not to interfere with the stack of magazines.

It is apparent that, by means of the conveyer arm 144 or any other suitable mechanism, the magazine or other article may be directly deposited upon the wrapper when positioned upon the operating table. Preferably, however, and in order that the wrapper may not be displaced by the magazine as it is positioned thereon, the free or leading end of the wrapper being preferably unconfined as previously described, I provide, in the present type of the invention, a suitable device, herein a tray, adapted to receive the magazine and to deposit the same upon the wrapper. While the described intermediary between the conveyer arm and the wrapping table may obviously be operated in any suitable manner to deposit the magazine, herein I impart thereto a movement of semi-rotation, so as to invert the magazine upon the wrapper. Viewing Figs. 2, 3 and 5, the magazines are preferably stacked upon the various shelves 115 with the backs thereof toward the endless chains forming the carrier, so that the top or bottom edge of the magazine is presented to the face of the conveyer arm 144.

Mounted in suitable guide ways in the framing of the machine (see Figs. 1, 2 and 6) is a vertical rack 149, with which meshes a pinion 150 fast upon a horizontally disposed shaft 151 (see Figs. 3 and 6). Pivotedly connected to the rack 149 (see Fig. 1) is a link 152, to the lower arm whereof is pivotally connected an arm 153 of a bell crank lever pivoted at 154 in the framing of the machine, the opposite arm 155 of said lever having thereon a roll 156 adapted to engage a cam path 157 in a cam 158 mounted on the main drive shaft 2, whereby, during the rotation of said shaft, a movement of vertical reciprocation is imparted to said rack, thereby to rotate the shaft 151 at a

variable speed, dependent upon the contour 65 of the cam path 157.

As shown most clearly in Fig. 3, there extends from the shaft 151 an arm 159 loosely connected thereto and having formed with or mounted upon the outer portion 70 thereof a tray 160 (see also Fig. 2), the inner portion whereof is provided with an upstanding edge 161. If desired, the edge portions of the framing may be provided, as shown in Figs. 2 and 5, with guide ways 75 162 and 163 extending at right angles to the upstanding edge 161 of the tray, so as to guide the movement of the magazine or other article when it is pushed into the tray by the conveyer arm 144. Splined upon the shaft 151, as represented in Fig. 3, is an eccentric 164, surrounding which is an eccentric strap 165 having projecting therefrom an arm 166, the outer end whereof is pivotally connected at 167 to an angular member 168, constituting the movable upstanding edge of the tray. Preferably the arm 166 is made in two parts, the inner member thereof being tubular to receive for yielding, sliding movement therein the member 169, said members being connected by a spiral spring 170 mounted between a shoulder 171 formed upon the member 166, and a pin 172 mounted upon the tubular member and passing through longitudinal 95 slots in the member 169. Fast upon the shaft 151 (see Fig. 3) is a cam 173, herein formed as a flange extending substantially half way about the shaft 151 to provide shoulders 174 and 175. From the described 100 operation of parts, it will be apparent that the topmost magazine or other article, having been pushed from the stack, falls upon the bottom of the tray 160, and that upon the movement of the shaft 151 clockwise or 105 in the direction of the arrow shown in Fig. 3, the eccentric 164 acts to move inward or to the right the tray edge 168 until the same engages the edge of the magazine or other article, such movement of the eccentric continuing until the spring 170 yields, whereby 110 the magazine is gripped with a yielding pressure. Upon such described movement of the shaft 151, the shoulder 174 of the cam 173 moving clockwise viewing Fig. 3, engages the under portion of the arm 159, whereupon, during the continued movement 115 of said shaft 151, the tray 161 is lifted by said shoulder, the eccentric 164 continuing to hold the edge 168 gripped against the adjacent edge of the tray. The movement of the shaft 151 in a clockwise direction continues throughout the downward movement 120 of the rack 149, but upon the commencement of the reversal of the movement of the rack the eccentric 164 acts to move the edge 168 from the adjacent edge of the magazine, 125 thereby releasing the same and permitting it

to drop upon the wrapper upon the operating table.

Inasmuch as in the present type of the invention the tray 160 is loosely mounted upon the shaft 151, I provide means to prevent overmovement of the tray as the same is inverted. It is apparent that any suitable mechanism may be employed for the purpose. Herein and as most clearly represented in Figs. 2 and 6, I form upon the arm 159 of the tray a lug 176, having means to engage a friction face 177 formed upon a portion of the framing. Preferably, in the lug 176 is mounted an adjusting screw 178, whereby the desired degree of friction may be secured against the face 177, so that during the downward movement of the tray to deposit the magazine or other article upon the wrapper, the said tray may not move ahead of the shoulder 174 of the cam 173. The contour of the cam path 157 and the timing of the parts are such that at the point of extreme downward movement of the rack 149, the tray assumes its lowest inverted position. The movement of the rack then being reversed, the shaft 151 rotates contra-clockwise viewing Fig. 3, until the shoulder 175 engages the upper face of the arm 159, further movement of the shaft 151 in said direction compelling the return of the tray into position to receive therein another magazine, the shape of the eccentric 164 being such that the movable edge 168 is removed from the tray to permit the ready insertion of another magazine thereto. The return movement of the tray is cushioned by the screw 178 bearing against the friction face 177.

Having thus described my invention, I desire it to be understood that although specific terms are employed, they are used in a generic and descriptive sense and not for purposes of limitation, the scope of the invention being set forth in the following claims.

1. In a wrapping mechanism, an operating table, means to deliver a wrapper thereonto, means to deposit a magazine or the like upon the wrapper, means to insert an edge of the wrapper between the leaves of the magazine, and periodically acting means to tighten the non-inserted portion of the wrapper relative to the magazine.

2. A wrapping mechanism comprising an operating table, means to deliver a wrapper thereonto, means to deposit a magazine or the like by inversion upon the wrapper, and means to insert an edge of said wrapper between the leaves of the magazine.

3. A wrapping mechanism comprising an operating table, means to deliver a wrapper thereonto with the free edge thereof unconfined, means to position the article to be wrapped on said wrapper, means to move said wrapper and article from said table,

and positively acting means to draw upon the rear end of the wrapper as it is moved from the table.

4. A wrapping mechanism comprising an operating table, means to deliver a wrapper thereonto, means to deliver an article upon the wrapper, a roll adapted to bear upon the rear edge of the wrapper, and means to lift said roll to permit the feeding of the wrapper to the table. 75

5. A wrapping mechanism comprising an operating table, means to deliver a wrapper thereonto, means to deliver an article upon the wrapper, a roll adapted to bear upon the rear edge of the wrapper, means to lift said roll to permit the feeding of the wrapper to the table, and means to move said roll into engagement with the rear end of the wrapper to draw thereupon and tighten the wrapper about the article to be wrapped. 80

6. A wrapping mechanism comprising an operating table, upon which a magazine to be wrapped may be positioned upon its wrapper, and means to open the pages of the magazine to receive the wrapper while the magazine is stationary in wrapping position upon the table. 85

7. A wrapping mechanism comprising an operating table, means to deliver a wrapper thereonto so that it is extended thereon, 95 means to superimpose a magazine upon the wrapper while so extended, and means to open the pages of the magazine transversely of the table to receive an edge of the wrapper. 100

8. A wrapping mechanism comprising an operating table, means to deliver a wrapper thereonto, means to deliver a magazine upon the wrapper so as to leave the wrapper's leading edge as delivered exposed, means to 105 separate the leaves of the magazine when the latter is in position to receive between the separated leaves the said leading edge of the wrapper, and means to insert such leading edge when the magazine is so positioned. 110

9. A wrapping mechanism comprising an operating table, means to deliver a wrapper thereonto with the leading edge as delivered unconfined, means to superimpose a magazine upon the wrapper leaving the said leading edge exposed, means to separate the leaves of the magazine, means to lift the said leading edge of the wrapper, and means to insert the lifted edge between the separated leaves of the magazine. 115

10. A wrapping mechanism comprising an operating table, means to deliver a wrapper thereonto with the leading edge unconfined, means to deposit by inversion a magazine on the wrapper, means to separate the leaves 125 of the magazine, means to insert the leading edge of the wrapper between said leaves, means to remove the magazine and wrapper from said table, and means to apply an adhesive to the rear edge of the wrapper. 130

11. A wrapping mechanism comprising an operating table upon which a wrapper and a magazine may be positioned, a working head, means to reciprocate the same toward and from the magazine when the latter is positioned upon the wrapper, and means operatively connected to said head to separate the leaves of the magazine.
12. A wrapping mechanism comprising an operating table, upon which a wrapper and a magazine may be positioned, a working head, and means operated thereby to separate the leaves of the magazine when superimposed upon the wrapper, to lift the leading edge of the wrapper and to insert such leading edge between the separated leaves of the magazine.
13. A wrapping mechanism comprising an operating table, means to deliver a wrapper thereonto, means to deliver a magazine upon the wrapper with the leading edge of the wrapper extending beyond said magazine, a working head, a secondary head, means carried by said secondary head to separate the leaves of the magazine, and means carried by said working head to insert the leading edge of the wrapper between the separated leaves of the magazine.
14. A wrapping mechanism comprising an operating table, upon which a wrapper and a magazine may be positioned with the magazine lying upon the wrapper, a working head, and a secondary head, means carried by said secondary head to separate the pages of the magazine when lying upon the wrapper, stationarily mounted means to lift the free edge of the wrapper, and means carried by the working head to insert the said edge of the wrapper between the separated leaves of the magazine.
15. A wrapping mechanism comprising an operating table, means to deliver a wrapper thereonto, means to deliver a magazine upon said wrapper, a working head, a secondary head, said secondary head being operated by said working head but adapted to be disengaged therefrom, an opener carried by said secondary head and adapted to be inserted between the leaves of the magazine, means mounted upon the frame of the machine and adapted to be operated in advance of the plane of the edge of the magazine to lift the leading edge of the wrapper, and means mounted upon the working head to insert the leading edge of the wrapper between the leaves of the magazine.
16. A wrapping mechanism comprising an operating table upon which a wrapper and a magazine or the like may be positioned with the magazine upon and contacting with the wrapper, means to insert an edge of the wrapper between the leaves of the magazine, a receiver for the wrapped magazine, means to deliver the wrapped magazine into the receiver, and means to eject the wrapped magazine from the receiver.
17. A wrapping mechanism comprising an operating table, upon which a wrapper and article to be wrapped may be positioned, means for positioning the wrapper about the article while the latter is maintained unfolded, a receiver for the wrapped article, means to apply an adhesive to the rear edge of the wrapper during the passage of the wrapped article from the operating table, and means to eject the wrapped article from the receiver.
18. A wrapping mechanism comprising an operating table, means to feed a wrapper thereonto, means to deliver a magazine upon the wrapper, means to separate the leaves of the magazine, means to throw such leaf separating mechanism out of action, and means to insert the leading edge of the wrapper between such separated leaves.
19. A wrapping mechanism comprising an operating table adapted to receive a wrapper and an article to be wrapped with the article upon and contacting with the wrapper, a receiver for the wrapped article, means to deliver the wrapped article unfolded into the receiver, a device for applying an adhesive to the rear edge of the wrapper, means to move said device into contact with such edge of the wrapper during the delivery of the article and wrapper into said receiver and means to move the receiver into article ejecting position.
20. A wrapping mechanism comprising an operating table adapted to receive a wrapper and article to be wrapped, a receiver for said wrapped article, means to deliver the wrapped article unfolded into the receiver, means to eject the wrapped article from the receiver, and simultaneously acting means to operate said deliverer and ejector at speeds differing from each other.
21. A wrapping mechanism comprising an operating table adapted to receive a wrapper and an article to be wrapped, a receiver for the wrapped article having a plurality of pockets, means to deliver the wrapped article into the receiver, means to eject the wrapped article from the receiver, means to position said receiver with one pocket thereof in alignment with the article upon the operating table and another in alignment with the ejector, and means to operate said delivery mechanism and said ejecting mechanism at differential speeds.
22. A wrapping mechanism comprising an operating table, upon which the wrapper and magazine or the like to be wrapped may be positioned, means to position an edge of the wrapper between the pages of the magazine, a receiver for the wrapped magazine, means intermittently to rotate the same, said receiver having a plurality of pockets, a

wrapped may be superimposed upon the wrapper, said table having a delivery throat, a receiver for the wrapped article, means to deliver the article from the table into the receiver, and means to apply an adhesive to the rear edge of the wrapper as it passes through said delivery throat.

35. A wrapping mechanism comprising an operating table, a guide way along which a 10 wrapper may be delivered thereto, means for feeding a wrapper along said guide way and upon said operating table with the leading edge thereof unconfined, means to engage the wrapper toward the opposite edge there- 15 of after the wrapper has been positioned to receive an article thereon, means to de- 20 posit the article upon the upper surface of the wrapper when the opposite edge is so engaged, and means to wrap the article in an unfolded condition.

36. A wrapping mechanism comprising an operating table, means to deliver a wrapper upon said table and to position the same thereon with the leading edge thereof free, 25 means to place a magazine or the like upon said wrapper, so that it is superimposed thereon, means to insert an edge of said wrapper between the leaves of the magazine, and means to deliver the magazine uncon- 30 fined from the operating table in such condition.

37. A wrapping mechanism comprising an operating table adapted to receive a wrapper thereon with the leading edge thereof free, 35 means to engage the rear edge of such wrapper, means to insert the leading edge of said wrapper between the leaves of a magazine or the like placed upon said wrapper when the latter is upon the operating table, and means to deliver such magazine or the like from the operating table by movement of said magazine in the plane of 40 the operating surface of said table.

38. A wrapping mechanism comprising an operating table adapted to receive a wrapper thereon with the leading edge thereof free, means to engage the rear edge of such wrapper, means to apply the leading edge of said wrapper to an article placed upon the 50 wrapper, means to deliver such article from the operating table in such condition, and means to apply the wrapper to the upper face of the article as it is delivered from said table.

39. A wrapping mechanism comprising an operating table, means to deliver a wrapper thereonto with the leading edge thereof free, means to position an article upon such wrapper, means to apply one edge of the 55 wrapper to an adjacent edge of the article, means to deliver the article and wrapper from the table in such condition, and means to apply the wrapper to the upper face of the article and to stretch the same there-

about as the wrapper and article are delivered from the table.

40. A wrapping mechanism comprising an operating table, a receiver for the wrapped article having a pocket adapted to be brought into alignment with the face of the 70 table, means to deliver a wrapper upon the table with the leading edge thereof free, means to position an article upon the wrapper, means to apply the leading edge of the 75 wrapper to the corresponding edge of the article, a working head to deliver the article and wrapper into said pocket, and means to apply the wrapper to the upper face of the article, to stretch said wrapper and to apply an adhesive to the rear edge thereof as said 80 wrapper and article are delivered into the receiver.

41. A wrapping mechanism comprising an operating table, means to deliver a wrapper thereonto, means to apply the leading edge 85 of the wrapper to the corresponding edge of an article placed thereon, a receiver for the wrapped article having one or more pockets therein, means to deliver the article and wrapper from the table into a pocket 90 of the receiver, means to deliver the wrapper to the upper face of the article during such delivery, means to apply an adhesive to the rear edge of the wrapper, and means to fold such rear edge upon the body of the wrapper. 95

42. A magazine wrapping mechanism comprising an operating table, adapted to receive a wrapper thereon, means to position the magazine upon said wrapper, an opener adapted to enter between the adjacent corners of the magazine to separate the leaves thereof, and means upon opposite sides of 100 said opener but in the rear of the leading end thereof to fold the leading edge of the wrapper between said separated leaves. 105

43. A magazine wrapping mechanism comprising an operating table, means to deliver a wrapper thereonto, means to position a magazine upon the wrapper, an opener to enter between the leaves of the magazine, 110 means to operate said opener, means to fold the leading edge of the wrapper between the opened leaves of the magazine, and means to withdraw the opener from the magazine by relative movement of said 115 opener and magazine.

44. A magazine wrapping mechanism comprising an operating table to receive a wrapper, means to feed a magazine onto said wrapper with the front edge of the magazine toward the free edge of the wrapper, an opener, means to insert the opener between the leaves of the magazine between the top and bottom edges thereof, means to insert the edge of the wrapper between said 120 separated leaves, and means to withdraw the opener. 125

45. A wrapping mechanism comprising an

- working head and an ejector adapted to deliver the wrapped article into the receiver and to eject it therefrom.
23. A wrapping mechanism comprising an operating table, upon which the wrapper and article to be wrapped may be positioned with the article flatwise for wrapping, a receiver for the wrapped article, means intermittently to rotate the same, said receiver having a plurality of pockets, article delivering mechanism and an ejector adapted to deliver the wrapped article into the receiver and to eject it therefrom, and means differentially to operate said article delivering mechanism and said ejector.
24. A wrapping mechanism comprising an operating table adapted to receive a wrapper and an article to be wrapped thereon, a receiver having pockets therein, a working head and ejector adapted respectively to deliver the wrapped article into the receiver and to eject it therefrom, and rack and pinion speed multiplying mechanism between the ejector and the working head.
25. A wrapping mechanism comprising an operating table to receive a wrapper and an article to be wrapped, a receiver for the wrapped article adapted to receive a plurality of articles, a working head to deliver the wrapped article into the receiver, an ejector to discharge the wrapped article from the receiver, a common operating means for said ejector and working head, and speed increasing mechanism between said ejector and said working head whereby the working head is operated at a greater speed than the ejector.
26. A wrapping mechanism comprising an operating table, a receiver having a plurality of pockets therein, a working head and ejector adapted respectively to deliver the wrapped article into the receiver and to eject it therefrom, a common means to reciprocate said working head and ejector, and a rack and pinion mechanism interposed between said ejector and working head, thereby to operate them at differential speeds.
27. A wrapping mechanism comprising an operating table adapted to receive a wrapper and an article to be wrapped, a receiver having a plurality of pockets, a working head and an ejector adapted respectively to deliver the wrapped article into the receiver and to eject it therefrom, and means to reciprocate said working head at a greater speed than the ejector.
28. A wrapping mechanism comprising an operating table adapted to receive a wrapper and an article to be wrapped, a receiver having a plurality of pockets therein, means to rotate the same intermittently, a working head and an ejector adapted respectively to deliver the wrapped article unfolded to the receiver and to eject it therefrom, a main drive shaft, and common operative connec-
- tions between said main shaft and said working head and ejector to reciprocate said working head and ejector.
29. A wrapping mechanism comprising an operating table to receive a wrapper and an article to be wrapped, a receiver having pockets therein for the wrapped article, the main framing of the machine having spaced, parallel guide ways therein a working head and an ejector spaced apart but in substantial parallelism and adapted respectively to deliver the wrapped article into the receiver and to eject it therefrom, and means to operate said working head and ejector said working head operating in the plane of the article upon the operating table.
30. In a wrapping mechanism, an operating table, a receiver adapted to receive wrapped articles therefrom, said receiver having pockets therein open at front and rear, a working head adapted to deliver an unfolded wrapped article into the pockets, and an ejector adapted to enter each pocket in turn through an open end thereof and to eject the article through the opposite open end.
31. A wrapping mechanism having an operating table to receive a wrapper and an article to be wrapped, a receiver for the wrapped article having a plurality of pockets, each pocket being open at the receiving end and having spaced webs at the opposite end, a working head to deliver a wrapped article into each pocket in turn and an ejector having its leading edge formed to enter between the spaced webs of each pocket to discharge the article from the open end thereof.
32. A wrapping mechanism comprising an operating table, means to deliver a wrapper thereonto, means to deliver a magazine upon the wrapper, means to separate the leaves of the magazine, means to elevate the leading edge of the wrapper, means to insert such edge between the separated leaves of the magazine, a receiver adapted to receive the wrapped articles, means to apply an adhesive to the rear edge of the wrapper, means to eject the wrapped article from the receiver, and means to fold the pasted edge of the wrapper onto the body thereof.
33. A wrapping mechanism comprising an operating table, means to deliver a wrapper thereonto with the leading edge thereof free, means to invert a magazine upon the wrapper, means to enter between the leaves of the magazine to separate the same, means to insert the leading edge of the wrapper between such separated leaves, means to stretch the wrapper about the magazine, means to apply an adhesive to the rear edge of the wrapper, and means to fold such rear edge upon the wrapper.
34. A wrapping mechanism comprising an operating table upon which an article to be

operating table adapted to receive a wrapper, a tray to receive a magazine to be wrapped, means to invert said tray about an axis substantially parallel to the longitudinal axis of the operating table to deposit the magazine upon the wrapper on the table and means to insert an edge of said wrapper between the leaves of the magazine.

46. A magazine wrapping mechanism comprising an operating table adapted to receive a wrapper, a support for the magazine, means to receive a magazine from the support and to position the same upon the table flatwise upon a wrapper positioned thereon, means to insert an edge of the wrapper between the leaves of the magazine transversely of the table and means to complete the wrapping of the magazine.

47. A magazine wrapping mechanism comprising an operating table, a magazine carrier, means automatically to operate the same, means to receive magazines individually from said carrier and to deposit the same upon the table and means to insert an edge of the wrapper between the leaves of the magazine.

48. A wrapping mechanism comprising an operating table adapted to receive a wrapper thereon, a holder adapted to receive a magazine or the like therein, means to invert the holder, thereby to deposit the magazine upon the wrapper, and means to apply the wrapper to the magazine, including means to insert an edge of the wrapper between the leaves of the magazine.

49. A magazine wrapping mechanism comprising an operating table adapted to receive a wrapper, a magazine receiving holder, gripping means to grip the article in the holder, means positively to operate said gripping means to grip the article, means to discharge the magazine upon the table, and means to apply the wrapper to the magazine including means to insert an edge of the wrapper between the leaves of the magazine.

50. A magazine wrapping mechanism comprising an operating table adapted to receive a wrapper, a holder to receive a magazine to be wrapped, means to move said holder to invert said magazine upon the table, positively acting means to grip the magazine during inversion, and means to apply the wrapper to the magazine including means to insert an edge of the wrapper between the leaves of the magazine.

51. A magazine wrapping mechanism comprising an endless carrier adapted to receive stacked magazines, means intermittently and automatically to operate said carrier, a tray, and means automatically to discharge the magazines singly into said tray, means to grip a magazine positioned in said tray, means to invert said tray to discharge the magazine therefrom and means to apply the wrapper to each magazine.

52. A magazine wrapping mechanism comprising an operating table, means to supply a wrapper thereto, an endless carrier, means automatically and intermittently to operate the same, means to discharge a magazine from said carrier, the operating means for said carrier being controlled by the discharge of the magazines from said carrier, a tray into which the magazines are received from said carrier, means to discharge the magazine from the tray upon the wrapper upon said table and means to apply the wrapper to the magazine.

53. A magazine wrapping mechanism comprising an operating table, an endless carrier to receive stacked magazines, means dependent upon the discharge of the magazines from the carrier for operating said carrier, a tray to receive magazines discharged from said carrier, means to feed a wrapper to said operating table, and means to deliver a magazine from the tray upon said wrapper with a free edge of the magazine toward the free edge of the wrapper.

54. In a wrapping mechanism an operating support upon which a wrapper may be positioned flatwise and upon which wrapper when so positioned a magazine or the like may be deposited for wrapping, means to insert an edge of the wrapper between the leaves of the magazine, and means to complete the wrapping operation including means to tighten the wrapper about the magazine or the like.

55. A wrapping mechanism comprising a wrapping table adapted to receive a wrapper, a carrier, a tray between the carrier and table, means to deposit a magazine or the like in said tray, means to grip the edges of said magazine in said tray, means to invert the tray to deposit the magazine on the wrapper upon the table, means to release said gripping means, and means to apply the wrapper to the magazine, including means to insert an edge of the wrapper between the leaves of the magazine.

56. Wrapping mechanism comprising a wrapping table adapted to receive a wrapper, a carrier for stacked articles, a tray, means to deliver articles from the carrier into the tray, rack and pinic mechanism to grip an article in the tray, and to invert the tray, means to prevent over movement of the tray during the inversion thereof and means to apply wrappers to said articles successively.

57. Wrapping mechanism comprising a wrapping table to receive a wrapper, a tray adapted to receive a magazine or the like to be wrapped, yielding means to grip said magazine in said tray by the edges thereof, means to invert said tray upon said table, thereby to deposit the magazine thereon, means to prevent over movement of the tray during inversion thereof, and means to in-

sert an edge of said wrapper between the leaves of the magazine.

58. A wrapping mechanism comprising a wrapping table adapted to receive a wrapper, a tray adapted to receive an article to be wrapped, a shaft, said tray being loosely mounted upon said shaft, gripping mechanism mounted upon said shaft to grip the article in said tray, means fast upon said shaft to invert said tray, means to prevent over movement of the tray during the inversion thereof and means to apply a wrapper to said article.

59. Wrapping mechanism comprising a wrapping table adapted to receive a wrapper, a shaft, means to operate the same, a tray loosely mounted upon said shaft, means mounted upon said shaft yieldingly to grip the edges of an article in said tray, means fast upon said shaft to invert said tray, friction means to prevent over movement of the tray during inversion, means to release the gripping means upon inversion of the tray and means to apply a wrapper to said article.

60. Wrapping mechanism comprising a wrapping table adapted to receive a wrapper, an endless carrier, a shaft, gearing between said shaft and said endless carrier, a clutch upon said shaft, means to discharge articles from said carrier, means controlled by the discharge of said articles therefrom to operate said clutch, whereby the carrier is intermittently operated a tray adapted to receive articles from said carrier and to deposit the same upon the table, and means to apply wrappers to said articles.

61. Wrapping mechanism comprising a wrapping table adapted to receive a wrapper, a carrier to receive stacked articles, means automatically and intermittently to operate said carrier, reciprocating mechanism to discharge articles from said carrier, a tray to receive articles from said carrier, means to grip articles in said tray, rack and pinion mechanism to invert said tray, thereby to deposit articles upon said table, means to release the gripped article from the tray and means successively to apply wrappers to said articles.

62. Wrapping mechanism comprising a wrapping table, a main drive shaft, means to deliver a wrapper upon said table, operative driving connections between said means and said main drive shaft, a receiver for wrapped articles, means intermittently to rotate the same, said receiver having a plurality of pockets therein, means to deliver a wrapped article into the receiver, means to eject a wrapped article from the receiver, means to reciprocate said delivery means and said ejector, differential mechanism intermediate said ejector and said delivery mechanism, automatic means for presenting stacked articles, and means inter-

mittently to invert articles from said stack singly upon said wrapper.

63. Wrapping mechanism comprising an operating table, means including a wrapper support to deliver a wrapper thereonto, means to deliver an article onto the wrapper, a roll adapted to bear upon the rear portion of the wrapper, said roll contacting with said wrapper when the article is upon the operating table, and means relatively to move the roll and the wrapper support to separate the same and permit the feeding of the wrapper to the table.

64. A wrapping mechanism comprising an operating table, means to deliver a wrapper thereonto, means to deliver a magazine upon the wrapper, a magazine opener, means to insert the same between the leaves of the magazine, and means to lift the inserted edge of the opener when between the leaves of the magazine.

65. Wrapping mechanism comprising an operating table, adapted to receive a wrapper and a magazine, a magazine opener, means to insert the same between the leaves of the magazine, and means relatively to move the opener and operating table from each other, thereby to separate the leaves of the magazine.

66. Wrapping mechanism comprising an operating table adapted to receive a wrapper and a magazine, a magazine opener, means to insert the same between the leaves of the magazine, and means to lift said opener, thereby to separate the pages of the magazine.

67. Wrapping mechanism comprising an operating table, upon which the wrapper and magazine may be positioned, a working head, means operated thereby to separate the leaves of the magazine, to lift the leading edge of the wrapper and to insert such leading edge between the separated leaves of the magazine, and means to discharge the magazine from the operating table by movement of the magazine in substantially the plane of the operating face of the table.

68. Wrapping mechanism comprising an operating table upon which the wrapper and article to be wrapped may be positioned, a receiver for the wrapped article, means to deliver the wrapped article into the receiver by movement of the article in substantially the plane of the surface of the operating table and means to eject the wrapped articles individually from the receiver.

69. Wrapping mechanism comprising an operating table upon which a wrapper and magazine or the like may be positioned with the magazine upon and contacting with said wrapper, means for positioning the wrapper about the magazine including means to insert an edge thereof between the leaves of the magazine, a receiver for the wrapped magazine, and means to apply an

adhesive to the wrapper transverse to the path of movement of the magazine into the receiver.

70. Wrapping mechanism comprising an operating table upon which a wrapper may be received and upon which wrapper a magazine or the like may be deposited when said wrapper is in wrapping position, means for wrapping the magazine, including means for inserting an edge of the wrapper between the leaves of the magazine, a receiver for the wrapped magazine, and means to apply an adhesive to the wrapper transverse to the path of movement of the magazine into the receiver during the passage of the wrapped magazine from the operating table.

71. A wrapping mechanism comprising an operating table adapted to receive a wrapper and an article to be wrapped, a receiver for the wrapped article, means to deliver the wrapped article flatwise and unfolded into the receiver, a device for applying an adhesive to the rear edge of the wrapper, and means to move said device into contact with such edge of the wrapper during the delivery of the article and wrapper into said receiver.

72. A wrapping mechanism comprising an operating table adapted to receive a wrapper and article to be wrapped, a receiver for said wrapped article in the plane of the operating table, means to deliver the wrapped article into the receiver, means to eject the wrapped article from the receiver, and positively acting means to operate said deliverer and ejector at speeds differing from each other.

73. A wrapping mechanism comprising an operating table adapted to receive a wrapper and an article superimposed upon the wrapper when on the table means to wrap the wrapper about the article without folding the latter, a receiver for said wrapped article, means to deliver the wrapped article into the receiver, means individually to eject the wrapped article from the receiver, and means to operate said deliverer and ejector at speeds differing from each other.

74. A wrapping mechanism comprising an operating table adapted to receive a wrapper and an article to be wrapped, means to wrap the article without folding it, a receiver for the wrapped article, means to deliver the wrapped article into the receiver, means to eject the wrapped article from the receiver, and differential speed mechanism between the delivery means and the ejecting means.

75. A wrapping mechanism comprising an operating table adapted to receive a wrapper and an article to be wrapped thereon, a receiver having one or more pockets therein, a working head and ejector adapted respectively to deliver the wrapped unfolded arti-

cle into the receiver and to eject it therefrom, and differential speed mechanism between the ejector and the working head.

76. A wrapping mechanism comprising an operating table adapted to receive a wrapper and an article to be wrapped thereon, a receiver having one or more pockets therein, a working head and ejector adapted respectively to deliver the wrapped article into the receiver and to eject it therefrom, and means to operate the working head at a greater speed than the ejector.

77. A magazine wrapping mechanism comprising an operating table adapted to receive a wrapper, means automatically to place a magazine upon said wrapper when positioned upon the table, and means to open the edges of the magazine transversely of the table to receive an edge of the wrapper when the magazine is so positioned upon the wrapper.

78. A magazine wrapping mechanism comprising an operating table adapted to receive a wrapper, means automatically to place the magazine upon said wrapper when positioned upon the table, means to open the leaves of the magazine when the latter is stationary upon the table, and means to insert an edge of the wrapper between the open leaves.

79. A magazine wrapping mechanism comprising an operating table adapted to receive a wrapper, means automatically to place a magazine upon said wrapper when the latter is extended flatwise upon the table, means to open the leaves of the magazine transversely of the table, means to insert an edge of the wrapper between the open leaves, and means to complete the wrapping of the wrapper about the magazine.

80. A magazine wrapping mechanism comprising an operating table adapted to receive a wrapper, means automatically to place a magazine upon said wrapper when spread upon the table, means to insert an edge of the wrapper transversely of the table between the leaves of the magazine, and means to apply an adhesive to the wrapper.

81. A wrapping mechanism comprising an operating table, means to deliver a wrapper thereonto, means to deposit by inversion a magazine or the like to be wrapped upon said wrapper and means to wrap the wrapper about the magazine by folding the wrapper along lines transverse to the table and inserting the edge thereof between the separated leaves of the magazine.

82. A wrapping mechanism comprising an operating table, means to deliver a wrapper thereonto, means to deposit a magazine directly onto the wrapper leaving the leading edge of the wrapper as delivered exposed, means to separate the leaves of the maga-

zine when upon the wrapper, and means to insert the said leading edge of the wrapper between the leaves of the magazine.

83. A wrapping mechanism comprising an operating table upon which the wrapper and an article to be wrapped may be positioned with the article upon and contacting with the wrapper, means to wrap the article while maintaining its normal shape, a receiver for the wrapped article, and means to eject the wrapped article individually from the receiver.

84. A wrapping mechanism comprising an operating table adapted to receive a wrapper and an article positioned flatwise on said wrapper, means to wrap the wrapper about the article, a receiver for the wrapped article, means to deliver the wrapped article into the receiver, means to eject the wrapped article from the receiver, and positive means to operate said deliverer and ejector at speeds differing from each other.

85. A magazine wrapping mechanism comprising an operating table adapted to receive a spread wrapper, means automatically to place a magazine upon said wrapper when spread upon the table, and means to open the pages of the magazine transversely of the table to receive an edge of the wrapper.

86. A wrapping mechanism comprising an operating table adapted to receive a wrapper and a magazine or the like superimposed upon the wrapper when on the table, means to insert an edge of the wrapper between the leaves of the magazine and to wrap the wrapper about the magazine, a receiver for said wrapped magazine, means to deliver the wrapped magazine into the receiver, means to eject the wrapped magazine from the receiver, and means to operate said deliverer and ejector at speeds differing from each other.

87. A magazine wrapping mechanism comprising a stationary operating table adapted to receive a wrapper, a support for the magazine, means to receive a magazine from the support and to position the same upon said stationary table flatwise upon a wrapper positioned thereon, means to insert an edge of the wrapper between the leaves of the magazine, and means to complete the wrapping thereof.

88. In a wrapping mechanism, an operating table, means to deliver a wrapper thereonto, means to deposit a magazine or the like upon the wrapper when the latter is extended upon the table, means to insert an edge of the wrapper between the separated leaves of the magazine, means to move the wrapper and article from said operating table, and means to tighten the rear edge of the wrapper as it is moved from the operating table.

89. In a wrapping mechanism, an operat-

ing table, means to deliver a wrapper thereonto, means acting in a plane substantially normal to the plane of the wrapper when upon the table to position the article upon the wrapper, means to wrap the article, means to push the article in front of it from said operating table, and means to tighten the rear end of the wrapper as it is moved from the operating table.

90. A wrapping mechanism comprising an operating table, means to deliver a wrapper thereonto with the free edge thereof unconfined, means to position the article to be wrapped upon said wrapper, means to move said wrapper and article from said table, means to draw upon the rear edge of the wrapper as it is moved from the table to tighten the same, and means to maintain said tightening means out of action during the delivery of the wrapper.

91. A wrapping mechanism comprising an operating table, means to deliver a wrapper thereonto with the free edge thereof unconfined, means to position the article to be wrapped upon said wrapper, means to move said wrapper and article from said table, and means to engage the rear edge of the wrapper to tighten the same prior to the commencement of the movement of the wrapper and article from the table.

92. A wrapping mechanism comprising an operating table adapted to receive a wrapper and article to be wrapped, a receiver for said wrapped article, means to deliver the wrapped article into the receiver, means to eject the wrapped article from the receiver, and means to operate said ejector at a less speed than said deliverer.

93. A wrapping mechanism comprising an operating table, adapted to receive a wrapper and article to be wrapped, a receiver for said wrapped article, means to deliver the wrapped article unfolded into the receiver, means to eject the wrapped article individually from the receiver, and means to operate said deliverer and ejector at speeds differing from each other.

94. In a wrapping mechanism, an operating support adapted to receive a wrapper and a magazine or the like, means to insert an edge of the wrapper between the leaves of the magazine, and means to complete the wrapping operation including means to draw upon the non-inserted portion of the wrapper by relative movement of the magazine and wrapper, thereby to tighten the wrapper about the magazine.

In testimony whereof, I have signed my name to this specification, in the presence of two subscribing witnesses.

ERNEST SCOTT.
